UNITED STATES PATENT OFFICE

2,098,323

GAUGE FOR COUNTING TYPEWRITTEN CHARACTERS

Harry L. Wadsworth, Los Angeles, Calif.

Application May 27, 1935, Serial No. 23,728

2 Claims. (Cl. 33—1)

This invention relates to and has for an object the provision of an improved form of gauge of transparent character adapted to be superposed on a sheet of typewritten manuscript in such a manner that an accurate and rapid totalization of the number of characters on a page of manuscript may be made for the purpose of determining the number of lines and the total space which a given manuscript will require when composed and set up in the same or a different type.

To this end the gauge is preferably formed of a sheet of non-combustible transparent material of rectangular form slightly larger than a sheet of manuscript and is provided with coordinal rulings vertically and horizontally which are preferably spaced apart respectively, to correspond to groups of five lines and groups of five characters, with marginal numerals representing the numbers of the lines on a page and numbers of characters in a line. Horizontal rows and vertical columns of numerals are provided adjacent the coordinal rulings for indicating the total numbers of characters in each line and in any number of lines on a page in multiples of five.

For convenience, I provide on the gauge a supplemental and auxiliary schedule of characters, in numerals arranged in a manner similar to these on the body of the gauge and including character totals for numbers of characters intermediate the multiples of five in a line i. e. one, two, three and four, and for the total number of lines on a page. Thus, the total number of characters on a page may be determined by adding the total ascertained from the main schedule and the total ascertained from the auxiliary schedule.

The gauge is also provided with a marginal ruling vertically formed at the left hand side of the main schedule of characters and adapted to be positioned between the first and second characters in each of the lines, and a horizontal ruling adapted to be positioned just below the top line of characters on a manuscript page.

By reference to characters it must be understood that I mean the actual characters including letters, numerals and punctuation marks together with the spaces between words, the total of all of which will be herein referred to as the total number of characters in a line. Usually typewritten manuscripts are printed in one of three different forms: pica type with pica line spacing, elite type with elite line spacing, and elite type with pica line spacing. Hence, a separate gauge is required for each of the three forms of manuscript copy, the only differences in the several forms consisting of differently spaced hor-

izontal and vertical rulings and character totals per line or lines.

A more detailed understanding of the invention may be had from the drawings hereto appended in which one form of gauge is shown and in which:

Fig. 1 shows a full size gauge partly broken away at the left hand side and omitting the auxiliary schedule of characters and showing a complete main schedule of characters for elite type 10 with pica line spacing;

Fig. 2 is a view of the portion of the gauge omitted from Fig. 1 and showing the auxiliary schedule of characters arranged at the left of the main character schedule;

Fig. 3 is a view of the complete gauge on a reduced scale and with the character schedules omitted but showing the coordinal rulings;

Fig. 4 is a fragmentary view of a manuscript and a gauge superposed thereon in position for 20 making a count of the characters in a manuscript.

The gauge is preferably made of a non-combustible, flexible and transparent sheet 1 of material on which I provide a main table 2 and an auxiliary table 3 of character totals, the totals 25 shown in table 2 being arranged by lines in multiples of five only while the totals in table 3 are arranged by lines in multiples of one, two, three and four. Thus, by adding the totals obtained in multiples of five to those obtained in multiples 30 of one, two, three or four, as the case may be, the final total of characters on a page is ascertained, as hereinafter described.

The tables 2 and 3 may be arranged for any given number of lines per page, but in the form 35 shown said tables are arranged to indicate the totals for sixty lines to a page; and said table 2 may vary in the number of characters per line, depending upon which of the type styles is used in a particular case.

Horizontal rulings 4, 4, etc., are provided at 40 regularly spaced distances apart to correspond exactly to the particular line spacing used in a manuscript M, and vertical rulings 5 are provided which are also regularly spaced to correspond to the spaces required for five characters of a particular type used. At the left hand margin of the table 2 I provide a vertical line 6, as a guide, which is spaced to the left from the nearest of the lines 5 to correspond to the space required for four characters, so that said line may be positioned between the first and second characters of each line on the manuscript, as shown in Fig. 4. A horizontal guide line 7 joins with the upper end of line 6 and is adapted to be posi- 55

tioned immediately below the first line of characters on a manuscript, as shown in Fig. 4. Preferably, the lines 6 and 7 are heavier than the lines 4 and 5 for more readily than otherwise positioning the gauge in character counting position on a manuscript, and said lines 6 and 7 may be formed in red ink if desirable.

The main table of character totals is formed in horizontal rows or lines 8 and vertical columns 10 9 with the totals, as hereinbefore mentioned, shown in multiples of five only. The auxiliary table 3 is arranged with horizontal rows 10 and columns 11 corresponding and supplementary to the table 2, and having the same number of horizontal rows as table 2 but only four vertical columns of totals. The auxiliary table, however, is not arranged in alignment with the rows of total on table 2.

In use, the gauge is positioned over a manuscript sheet or page with the vertical guide line 6 disposed between the first and second characters of each line of typing on the manuscript and the horizontal guide line 7 disposed below the first line of typing thereon, as shown in Fig. 25 4. Usually the length of the lines in a manuscript is fairly uniform, but any difference in line length may be compensated for by first ascertaining the number of characters in the shortest line of the manuscript and then ascertaining 30 the number of characters in the longest line and averaging the two results as a guide to the count to be made. For instance, assuming that the shortest line is indicated on the gauge as "67" characters in length and the longest line is "73" 35 characters in length, the average length of line in the manuscript would be "70" characters in length, as indicated by the character scale 12 at the top of the table 2. Hence, if the number of lines of characters on the manuscript were "45" 40 as indicated at the left hand side of the table 2 by the line scale 13 the total number of characters on that page of a manuscript would be found in the "70" column just above the "45" line 4 in table 2 which is ascertained to be "3150", by reference to the table in Fig. 1. In such case if the 45 number of lines on the manuscript should be 53 the total characters would be "3710" which total will be found in the table 2 just above line 4 on the fifty-third line of the table and in the 50 "70" column of totals.

In the above mentioned case, if the average number of characters in a line should be found not to be a multiple of five but an intermediate number between one of the numbered columns 55 of totals and a preceding or succeeding column, the exact total can be ascertained only by first obtaining the total from table 2 in the column 9 which is the next lowest multiple of five shown in the table, and then by reference to table 3 60 obtaining the total from the column 11 indicated by the digit corresponding to the difference between the next lowest multiple of five and the average character count in a line, and obtaining the total shown on the line from which the total 65 was taken in table 2.

Assuming that the average number of characters in a line of manuscript should be found to be "67", as hereinbefore described, and the number of lines of characters is fifty, the next lowest 70 multiple of five would be "65" and the total number of characters in fifty lines of average character length of sixty five is ascertained in table 2 to be "3250". Then, there being two characters per line in excess of the multiple sixty-five, by 75 reference to table 3, it will be ascertained that

the "2" column shows a total for fifty lines of "100". Thus, by adding the "3250" and the "100" so obtained, the final total is found to be "3350".

It will be understood, of course, that in type composition, the number of characters is the 5 most important factor and in order to predetermine the amount of space required to print a given manuscript it is necessary to first ascertain the space required. Space for given "copy" 10 of course depends upon the style of type used and the line spacing. There are but two styles of typewriter type in general use, namely, pica and elite, but pica line spacing is frequently used with elite type.

The number of characters in a manuscript, 15 regardless of the type style and the line spacing, having been ascertained, the conversion of the manuscript from one to another type style is readily accomplished and a composer is certain 20 of the amount of space required for the subject matter of the manuscript.

Each page of a manuscript is separately measured for counting the total number of characters thereon and the total is written on the page, and upon completion of the count for all pages 25 a grand total is obtained by adding the sub-totals on the several pages. Due allowance may be made in the count for spaces between paragraphs. For instance, if the gauge indicates fifty 30 lines of characters whereas seven lines of characters have for some reason been omitted the "7" is deducted from "50", leaving a balance of "43" which is the actual number of lines and the total for the page would be ascertained by reference to the row of totals on line forty three 35 in the particular vertical column which represents the nearest multiple of five to the average number of characters per line. Similar allowance may be made for double and triple spacing 40 of characters on a manuscript.

Each sheet of manuscript is regarded as a 45 separate unit in type composition as each may have its own characteristics and peculiarities, different spacing, etc. Long hand interlineations may or may not vitally affect the character count; but if too frequent and extensive, allowance may be made therefor, as well as for paragraph indentations and paragraph endings, where the omitted characters in lines are substantial 50 in number and too frequent.

I conceive it to be possible to modify my improved gauge, within the scope of the appended claims, without departing from the spirit of my invention.

What I claim as new and desire to secure by 55 Letters Patent is:

1. A gauge for counting typewritten characters comprising: a sheet of transparent material having tabularly arranged totals thereon in horizontal rows spaced to correspond to a predetermined 60 number of characters in a line and in vertical columns spaced to correspond to the line spacing of a selected style of type and adapted to be superposed on a sheet of manuscript so that the printed totals on the gauge will indicate the total numbers of characters on the manuscript at points 65 registering with said printed totals, horizontal rulings at regular intervals subdividing said rows into groups, and vertical rulings adjacent the left hand digits of said columns, and right angularly 70 extended guide lines adapted to register with characters on the manuscript to position the sheet for use, one of said guide lines being spaced to the left of the adjacent vertical column and adapted by reason of the transparency of the 75

sheet to be placed between the first and second characters on each line of manuscript over which the sheet is placed and the other guide line being disposed to be placed below the first line of characters of said manuscript.

5 2. A gauge for counting typewritten characters comprising: a sheet of transparent material provided with parallel horizontal and vertical rulings spaced apart horizontally to correspond to a pre-
10 determined number of character positions of a selected style of type and spaced vertically to correspond to a predetermined number of lines of characters, said horizontal rulings being spaced vertically so as to regularly group character
15 totals arranged in horizontal rows intermediate said horizontal rulings and in vertical columns intermediate said vertical rulings, said gauge

being adapted to be superposed on a sheet of manuscript with said rows of totals in registration with the lines of characters on the manuscript and said columns of totals in registration with predetermined character positions in the lines of the manuscript, for indicating the totals of characters at successive points, and marginal rulings at one side and at the top of the gauge for registration with predetermined lines of characters and characters in the lines for positioning the gauge on the manuscript, said marginal rulings being respectively positioned so that when the sheet is placed over manuscript said rulings will lie between the first and second characters of each line of script and beneath the first line of characters, respectively.
